STAPLING MACHINE

William Drypolcher, Valley Stream, N. Y.

Application June 11, 1935, Serial No. 25,973

15 Claims. (Cl. 1—49)

This invention relates to stapling machines, and more particularly to those known as the lever type, wherein pressure of one hand upon a lever operates to store energy in a compression spring, 5 which energy is subsequently released to drive a staple.

One of the problems connected with the use of a lever type stapling machine is the loading of the staples into said machine. The staples may 10 be loaded in from the rear of the machine. However, there are certain inherent advantages in loading the machine from the front end.

This is difficult to do under ordinary circumstances, because the compressive force of the 15 drive spring holds the driver plunger at its lowest position except during a brief moment when the driver is raised as the machine is being operated. Consequently the driver in its normal position lies in the path of and directly obstructs 20 the loading of staples into the machine.

In my Patent No. 2,033,516, granted March 10, 1936, I disclosed one method of overcoming this difficulty, by holding the entire driving mechanism upraised to a certain point where said mechanism will not interfere with the insertion of the 25 staples into the feed channel of the core. In other words, the mechanism is locked with the spring in compressed condition. Because of the powerful nature of the driving spring, this places 30 the parts under considerable stress. In my present application, I disclose a new and improved method of accomplishing the same purpose without holding the driving mechanism upraised adjacent the top of its stroke, or equally importantly, without holding the driving spring under 35 tension.

The primary object of my invention is to generally improve stapling machines. A more particular object of my invention is to provide an 40 easy and convenient method of loading a charge of staples into such a machine. A further object of the invention is to provide an easy and convenient method of clearing the channel of the machine should it become clogged. Another object is to adapt the same mechanism for facilitating both loading the machine, and clearing the 45 same when clogged. A still further object of the invention is to provide accurate and inexpensive means for the stated purposes.

To the accomplishment of the foregoing and other objects which will hereinafter appear, my invention consists in the stapling machine elements and their relation one to the other, as hereinafter are more particularly described in the 50 specification and sought to be defined in the 55

claims. The specification is accompanied by a drawing in which:

Figure 1 represents a perspective view of one type of stapling machine making use of my invention, with the forward bottom portion of the 5 casing cut away to expose the working parts;

Figure 2 represents a close-up view showing the loading of a charge of staples into the magazine;

Figure 3 is a rear view of the plunger and pivoted driving blade forming an important feature of my invention, with the blade in angular position;

Figure 4 is a front view of the plunger and pivoted driving blade; and

Figure 5 is a section taken in elevation through the staple driving mechanism of the machine.

In the particular machine illustrated in the drawing the staples are fed horizontally, and upon depression of manually operable lever 15, 20 the endmost or forward staple is driven downwardly by a spring pressed driver. The staples are loaded at the driving end of the machine, that is, from the right as viewed in Figs. 1 and 2. The driver 10 is disposed directly in the staple loading path, but in accordance with the present invention it may be moved independently of the plunger 14 and driving spring 22, the movement being adequate to entirely clear the staple loading path. More specifically, the driver 10 is pivoted on plunger 14, as is clearly shown in Figs. 2, 3 and 4. During operation the driver is held in driving position by appropriate guide means, and in accordance with the present invention, the guide means 6 is itself releasable to free the 35 driver 10, as will be seen by comparing Figs. 1 and 2. Moreover, the guide means 6 may be used also as a staple loading door, thus fully opening the machine to receive a new clip of staples, as is shown in Fig. 2, after moving merely the members 6 and 10 to open position. At the same time the spring 22 and plunger 14 remain in downward position, and are in no way affected by the loading operation.

Considering the machine in greater detail, the 45 device is shown to consist of a frame 1, into which is mounted a staple carrying core 2, containing a staple feed channel 21 (see Fig. 2) into which a supply of staples is placed, the staples being fed toward the driving mechanism by spring 3 50 (Fig. 1), the forward end of which bears against a washer 4 pushing against a substantially U-shaped staple feeder 5. The staples are urged forward by the pressure exerted by spring 3 until a staple contacts against the inside surface 10a 55

(Fig. 3) of the driver or blade 10. Blade 10 in its normal position lies in and is confined by a closed drive channel formed by the front surface of core 2 and the three inner side walls of door 6. Door 6 is formed substantially U-shaped when viewed in plan, and has a support arm or strip extending upward therefrom. Said arm has a piece 7 struck outwardly or otherwise formed thereon, and acting as a finger piece to facilitate opening the door. 10 In the bottom of the side portions of the U-shaped door are cut deep straight walled notches 9 which securely and dependably mate with locking projections 8 on the core. Secure anchorage is desirable because the closure or door 6 is relied upon to hold the driver or blade 10 in working position, which in the present case is in alignment with the plunger 14. Door 6 at its uppermost portion is rolled into a cylindrical form providing a hinge bearing 17 for a pin 18, the 20 ends of said pin being slidable in oblong slots 19 dimensioned to permit the door 6 to be raised upward until notches 9 clear their mating extensions 8. This permits the door to be swung outward as shown in Figure 2. Pin 18 is preferably higher than driver pivot 12, so that the door 6 when open will not obstruct full opening of driver 10, and in the arrangement shown both the door and driver may be moved upwardly to collateral horizontal position. 25 The machine includes a plunger 14 which is a substantially cylindrical shaped member hollowed at 20 (Fig. 4) to provide for the insertion of a driver compression spring 22 (Fig. 1). The lower part of the plunger is shaped to provide 30 for the insertion of bearing 11 which is pivoted on pivot pin 12 the ends of which are received in ears depending from the plunger. Bearing 11 contains solidly fixed in it a driver or driving blade 10. The top 13 of bearing 11 is accurately 35 machined off to such dimension that when driving blade 10 swings completely downward so as to be in line with the axis or longitudinal dimension of plunger 14, bearing surface 13 comes into solid or face to face contact with a complementary bearing surface at the bottom of the plunger. When the staple driving unit is in operation, this solid surface of contact relieves pivot pin 12, as the complete force of the blow is transmitted directly through the blade 10, bearing 11, through surface 13, into the plunger 14. 40

The machine is operated by a lever 15 onto which the pressure of the hand is placed, and as said lever is depressed, it in turn compresses the compression spring 22 and at the proper moment coacts to release the stored up energy in said spring, permitting it to forcibly drive down the plunger 14, thereby driving the end staple home into the material being stapled. 50

Referring to Fig. 5, the lever 15 is shown in the normal or "at rest" position. The forward end is vertically slotted or bifurcated at 23 and there carries a dog 24 pivoted at 25. The forward end 26 of dog 24 rests beneath plunger 14. As handle 15 nears the end of its down stroke the 55 rear end 27 of dog 24 rides against bar 28 which oscillates dog 24 counter-clockwise, thereby freeing plunger 14 which descends under the influence of compression spring 22. Handle 15 is restored by spring 29. The shock of the downward 60 blow of cylinder 14 is partially absorbed by cushioning spring 30.

16 represents an adjustment cap for varying the pressure of the compression spring.

The feed mechanism, the lever mechanism, the 65 adjustment and driving spring compressing ar-

rangement are well-known in various forms to those familiar with the art, and therefore require no further detailed description. The plunger with the pivoted driving blade and the door, however, are new and represent improvements in stapling machines which are important features of this invention. 5

The operation of the device is carried out as follows:

To load the machine, staple pusher 5 is pulled 10 backward toward the rear of the machine against the pressure of spring 3, and latched by conventional means if desired. Upward pressure is exerted by the thumb against projection 7, raising the entire door and causing pin 18 to slide 15 upwardly in slots 19. Simultaneously, slots 9 in the lower portion of the door are raised upward until they are above projections 8 whereupon continued pressure of the thumb or finger against finger piece 7 results in the door pivoting 20 outward about pivot pin 18. This is clearly illustrated in Figure 2.

The blade 10 and lower portion of plunger 14 are now revealed and the bottom of blade 10 is readily moved outward as shown in Figure 2 25 to the extent that a staple clip can be loaded into feed channel 21 of core 2. When the staples have been loaded completely into position, blade 10 is pivoted downwardly against the front end of core 2 and door 6 is pivoted downwardly 30 and then raised, and finally allowed to drop down so that notches 9 engage over projections 8. Staple slide 5 is then released and the pressure of feed spring 3 moves the clip of staples forward until the end staple is pressing against the 35 rear surface 10a of driving blade 10.

To use the machine pressure is placed upon lever or handle 15, thus raising the plunger 14 upward against the pressure of the compression spring 22, and as soon as the lower edge of driving blade 10 passes staple feed channel 21, a staple feeds out underneath the edge of the blade. A brief interval thereafter, the pressure stored up in the drive spring is released by suitable 40 means and the driving blade 10 is impelled forwardly on its downward path until the staple is 45 driven home.

Should the machine become clogged, the user has only to go through the operations of opening the door and pivoting said driving blade outward, picking off the clogged staple or staples with the fingers, and then pivoting back into position the driving blade and the door, the latter being locked in position. When the machine is opened the clogged staple is fully exposed and is in no 50 way confined, hence the clogged staple is very 55 readily removed.

It is believed that the mode of constructing and using, as well as the many advantages of my improved stapling machine will be apparent 60 from the foregoing detailed description thereof. The machine possesses all of the advantages of front loading, yet does not necessitate locking the actuating means or spring in elevated position. There is accordingly no excessive stress 65 on the working parts and no danger to the operator loading the machine with a new supply of staples. Moreover, the machine is cleared with particular ease should it become clogged. Although the driver is pivoted, the driving impact is not applied to the pivotal connection, but is instead applied directly to a broad, ample bearing surface. 70

It will be apparent that while I have shown and described my invention in a preferred form, 75

many changes and modifications may be made in the structure disclosed without departing from the spirit of the invention defined in the following claims.

5 I claim:

1. In a machine of the type specified, a casing, staple guide means, staple driving means, and resilient means normally urging the driving means across the guide means, said driving means being arranged to swing sidewardly sufficiently to clear the guide means in order to permit loading of staples into the guide means without preliminarily tensioning the resilient means.

10 2. In a stapling machine, a casing, a feeding and driving means in said casing, said driving means including a driver mounted on a plunger by means of a pivotal connection, said driver having a working position in which it is movable across the feeding means, said driver and plunger also having complementary surfaces adapted 20 to come into direct contact when the driver is in working position so as to relieve the pivotal connection from excessive pressure during the driving operation.

25 3. In a machine of the type specified, a staple guide core, spring feed means on said core, a plunger transversely reciprocable adjacent the forward end of said core, resilient means normally urging the plunger toward the core, said plunger carrying a driver oscillatably mounted on the plunger, said driver and plunger also having directly contacting bearings to take the driving pressure of the plunger on the driver when the driver is in working position, said driver being enclosed and guided in working position by a door, said door and said driver being swingable outward sufficiently to clear the forward end of the staple guide core in order to permit loading of staples on the core.

40 4. In a lever operated staple driving machine, a casing containing a core with staple feeding means for feeding staples on said core, staple driving means including a driver mounted on a pressure receiving member, a compression spring bearing against said pressure receiving member 45 and normally urging said driver across the loading end of said core, and a door guiding said staple driver at the end of the core, said door being movably mounted on said casing, and said driver being movably mounted on said pressure receiving member, the mountings being such that the door and the driver are movable away from said core without moving said spring, in order to permit loading of staples onto said core.

45 5. A stapling machine comprising a staple magazine closed at one end and open at the staple driving end of the machine for reloading, staple feed means adapted to feed the staples toward the staple driving end thereof, a staple driver movable transversely of the path of said feed means, actuating means for impelling said driver across the feed path, said actuating means being such as to normally hold the driver across the feed path, said driver and said actuating means 50 being so related that the driver may be readily manually moved independently of the actuating means to a position clear of the staple feed path in order to permit loading the feed means with a new supply of staples.

70 6. A stapling machine comprising a staple magazine closed at one end and open at the staple driving end of the machine for reloading, staple feed means adapted to feed the staples toward the staple driving end thereof, a staple 75 driver movable transversely of the path of said

feed means, a relatively powerful compression spring and a plunger moved thereby for impelling said driver across the feed path, said driver and plunger being so related that the driver may be readily manually moved independently of the plunger and spring to a position clear of the staple feed path in order to permit loading the feed means with a new supply of staples.

7. A stapling machine comprising staple guide means, a staple driver movable transversely of said guide means, resilient means for impelling said driver across the guide means and for normally holding it across the guide means when the machine is at rest, and actuating means to first compress and then release said resilient means when the machine is to be operated, said driver being oscillatable with respect to said resilient means so that the driver may be swung entirely out of the path of the guide means.

8. A stapling machine comprising staple feed means adapted to be loaded at the staple driving end thereof, a staple driver movable transversely of the path of said feed means, a relatively powerful compression spring and a plunger moved thereby for impelling said driver across the feed path, said driver and plunger being pivotally related so that the driver may be swung out of the path of the feed means in order to permit loading the same with a new supply of staples.

30 9. A stapling machine comprising staple guide means, a staple driver movable transversely of said guide means, a relatively powerful compression spring and a plunger moved thereby for impelling said driver across the guide means, said driver and plunger being pivotally related so that the driver may be swung out of the path of the guide means, and means to normally hold the driver in alignment with the plunger.

10. A stapling machine comprising staple feed means adapted to be loaded at the staple driving end thereof, a staple driver which in working position is movable transversely of the path of said feed means, a relatively powerful compression spring and a plunger moved thereby for impelling said driver across the feed path, said driver and plunger being pivotally related so that the driver may be swung out of the path of the feed means in order to permit loading the same with a new supply of staples, and releasable means to normally hold the driver in working position.

11. A stapling machine comprising staple guide means, a staple driver which in operative or driving position is movable transversely of said guide means, actuating means for impelling said driver across the guide means, said actuating means being such as to normally hold the driver across the guide means, said driver and actuating means being pivotally related so that the driver may be swung out of the path of the guide means, and a releasable closure at the staple driving end of the staple guide means, said closure including means to confine the driver to its operative or driving position when the closure is closed.

12. A stapling machine comprising staple feed means adapted to be loaded at the driving end thereof, a staple driver which in operative or driving position is movable transversely of the path of said feed means, resilient means and a plunger moved thereby for impelling said driver across the feed path and normally tending to hold it across the feed path, said driver and plunger being pivotally related so that the driver

may be swung out of the path of the feed means in order to permit loading the same with a new supply of staples, and a releasable closure at the driving and loading end of the staple guide means, said closure including means to confine the driver to its operative or driving position when the closure is closed.

13. A stapling machine comprising staple guide means, a staple driver movable transversely of said guide means, a relatively powerful compression spring and a plunger moved thereby for impelling said driver across the guide means, said driver and plunger being pivotally related so that the driver may be swung out of the path of the guide means, and a releasable closure at the driving end of the staple guide means, said closure including means to confine the driver to a position in alignment with the plunger when the closure is closed.

14. A stapling machine comprising staple guide means, a staple driver movable transversely of said guide means, a relatively powerful compression spring and a plunger moved thereby for impelling said driver across the guide means, said

driver and plunger being pivotally related so that the driver may be swung forwardly out of the path of the guide means, a closure at the driving end of the staple guide means, a pivot at the upper end of said closure, said pivot being located higher than the pivot of the driver, and means to lock the closure in closed position.

15. In a stapling machine, a staple core with staple feeding means for feeding staples along said core, said staple core being closed at the rear end and open at the forward end for reloading, staple driving means reciprocable at the forward end of said staple core, means to actuate the staple driving means, the normal position of said driving means between stapling operations being such as to block the end of the staple core, and openly accessible manually operable means whereby the staple driving means may be readily moved independently of the actuating means to a position clear of the staple core, in order to permit loading of a supply of staples onto the staple core.

WILLIAM DRYPOLCHER.
